COMBINED SMOKING STAND AND PIPE RACK

Salvador G. Messina, Baton Rouge, La., assignor to
Messina Smoking Stand, Inc., Baton Rouge, La., a cor-
poration of Louisiana

Filed Aug. 21, 1964, Ser. No. 81,394

Term of patent 14 years

(Cl. D85—2)

Fig. 3

Fig. 4

Fig. 5

FIGURE 1 is a side elevational view of a combined smoking stand and pipe rack showing my new design; FIGURE 2 is a front elevational view;

FIGURE 3 is a top plan view;

FIGURE 4 is a sectional view taken on the line 4—4 of FIGURE 1;

FIGURE 5 is a bottom plan view; and

FIGURE 6 is a fragmentary sectional view taken on the line 6—6 of FIGURE 2.

The dominant features of my design reside in the portions shown in full lines.

I claim:

The ornamental design for a combined smoking stand and pipe rack, substantially as shown and described.
